(57) **CLAIM**

The ornamental design for a flux applicator refill, as shown and described.

DESCRIPTION

FIG. 1 is a side view of a flux applicator refill, showing our new design;

FIG. 2 is a front perspective view thereof;

FIG. 3 is a bottom view thereof; and,

FIG. 4 is a top view thereof.

The broken lines in the figures illustrate the portions of the design that form no part of the claimed design.

1 Claim, 4 Drawing Sheets

FIG. 1

FIG. 2

FIG. 3

FIG. 4
